UNITED STATES PATENT OFFICE.

FRED M. SLATER, OF EASTON, PENNSYLVANIA, ASSIGNEE TO INGERSOLL-RAND COMPANY, OF JERSEY CITY, NEW JERSEY, A CORPORATION OF NEW JERSEY.

HOIST.

Application filed October 18, 1923. Serial No. 669,331.

This invention relates to hoists, but more particularly to a fluid actuated rotary cylinder motor hoist, in which the cylinders are arranged longitudinally of the hoist drum.

5 Hoists of this character are desirable in numerous places for haulage and hoisting purposes, as for instance in hauling a scraper for slushing ore and for hoisting timber in mines. It is essential that these hoists be 10 as light as practicable, so that they may be conveniently transported from place to place, yet they must be sturdy and rugged, to stand the hardest kind of usage. Other essential characteristics are, that they be 15 compact, simple in their construction, easily operated, and thoroughly protected from mud and grit, which would tend to injure the moving parts.

One of the objects of this invention, is to 20 enable a rotary cylinder motor to be placed within the drum of a hoist, in order to occupy less space and reduce the over-all length of the hoist.

Another object of this invention is to produce 25 a hoist in which the motor cylinders are arranged longitudinally within the hoist drum, suitable gearing being provided for operatively connecting the motor to the drum.

30 A further object is to generally improve upon fluid operated rotary cylinder motor hoists, so as to cheapen the cost of manufacture, reduce the number of parts and materially strengthen their construction.

35 Further objects of the invention will hereinafter appear, and the invention consists of the features of construction and combinations of elements as pointed out in the specification, defined in the appended claims and 40 shown in the accompanying drawings, in which

Figure 1 is a longitudinal vertical sectional view of a hoist,

45 Figure 2 is an end elevation partly in vertical section of the hoist shown in Figure 1 with the gear case and ring gear removed,

Figure 3 is a transverse sectional view taken on the line 3-3 of Figure 1, looking in the direction of the arrows,

50 Figure 4 is a view similar to Figure 3, showing a different position of the throttle valve,

Figure 5 is an enlarged detail fragmentary view partly in transverse section, taken on 55 the line 5-5 of Figure 1, looking in the di-

rection of the arrows, with the parts in a slightly different position, and

Figure 6 is a longitudinal sectional plan view taken on the line 6-6 of Figure 5, looking in the direction of the arrows. 60

Referring to the drawings, the cylinders Q of a fluid actuated rotary cylinder motor are located within the winding drum L, and have their axes parallel to the longitudinal axis of the drum, so that the weight 65 and the over-all length are reduced to a minimum, and an extremely compact hoist is produced. The pistons R reciprocate in the cylinders Q, and this reciprocating motion is translated into rotary motion of the 70 winding drum L through suitable connecting rods, cranks, crank shafts, and pinions, which mesh with a stationary ring e. In this manner, the motor rotates with the winding drum, and in order to distribute motive 75 fluid to the cylinders Q, a suitable valve j is provided which also serves to receive the pressure fluid exhausted from the cylinders. A suitable throttle valve 2 serves to control the admission of motive fluid to the motor 80 and this valve also operates as a reversing valve to control the direction of rotation of the winding drum L, so that the cable L' may be wound upon or unwound from the drum. 85

Referring more particularly to the drawings, the base plate A, on which the hoist is mounted, is provided with a saddle clamp B, so that the hoist may be supported on a column, cross bar or other support. In this 90 instance, a support C is formed on the base plate A at one end thereof and a head block D containing a valve chest D' is preferably secured to the support C by the bolts E. A gear case F is suitably secured to the base 95 plate A by bolts F' at the opposite end from the support C, and is in this instance formed with an inwardly extending boss G. A drum shaft H is supported at one end in the boss G of the gear case F and at the 100 other end in the head block D, and is preferably held against rotation by a suitable key J. Nuts K are threaded onto the opposite ends of the shaft H in order to prevent end-wise movement of the shaft. 105

A drum L is rotatably mounted on the shaft H and is in this instance formed with external circumferential flanges O and P at the opposite ends thereof. A cable L' is preferably secured to the drum L by a screw 110

L^2 so that the cable may be wound upon or unwound from the drum according to the direction in which the drum is rotated. In this instance, the interior of the drum L is 5 formed with a plurality of longitudinally arranged cylinders Q , preferably four in number, in which pistons R are adapted to reciprocate. Suitable connecting rods S connect the wrist pins T of the pistons R with 10 cranks U on the crank shafts V .

In this instance, the crank shafts V are mounted in anti-friction bearings W , which are secured to a bearing plate X by caps Y and bolts Z . The bolts Z also secure the 15 bearing plate to the drum flange P , so that the drum and bearing plate rotate together. The crank shafts V are preferably formed with suitable counterweights a , and nuts b on one end of the crank shafts prevent end- 20 wise movement of the crank shafts. A bevel pinion c is preferably secured to each crank shaft V by a suitable key d , and each bevel pinion meshes with a stationary beveled ring gear e , which is in this instance secured to 25 the gear casing F by bolts f , washers g , and nuts h . As the pistons R reciprocate in the cylinders Q , rotation is imparted to the bevel pinions c through the cranks U and crank shafts V , and the drum L is caused to 30 revolve as the bevel pinions rotate upon the stationary ring gear e .

A suitable valve j is provided to distribute motive fluid to the cylinders Q , and in this instance, the ends of the valve j are closed 35 by the caps k and o suitably secured to the valve and forming a part thereof. The cap o is provided with the bushed port p and the port q , one of which ports serves as an inlet port when the other acts as an exhaust port, 40 as will be hereinafter described. The circumference of the valve j is preferably formed with a series of ports r and series of ports s , which are separated from each other by a tortuous web t , so that the ports r alternate with the ports s around the valve, and all the ports r communicate through a passage q' with the port q in the cap o , and all the ports s communicate through a passage p' with the bushed port p in the cap o . 45 The distributing valve j may be integrally formed with the valve chest D' or stationary shaft H , if desired, but in this instance is a separate valve and a pin j' in the head block D is adapted to extend into the valve cap o 50 for centering the valve and holding it stationary on the shaft H . In order to take up wear between the drum L and distributing valve j , a bushing v is preferably secured to the drum for rotation therewith, and is 55 formed with ports w which are aligned with the passages u , four in number, leading to the motor cylinders Q .

Let it be assumed that the drum L is rotating in the direction of the arrow x shown in Figure 5, and motive fluid is admitted 60

through the port p in the valve cap o , then the ports s , which communicate with the port p , will serve to admit motive fluid to the cylinders Q through the ports w in the bushing v and passages u formed in the drum. A port s at the right hand of Figure 70 5, is admitting motive fluid to a cylinder Q , while a port r , which is diametrically opposite from the admission port s , is exhausting pressure fluid from one of the cylinders. 75 As all of the ports r are in communication with the port q , in the valve cap o , the port q in this instance serves as an exhaust port. The cylinder passage u at the upper portion 80 of Figure 5 is cut off, but about to be brought into registration with an admission port s , while the passage u at the lower portion of the figure is also cut off, but about to register with an exhaust port r . As the drum revolves about the valve j , there is first admission, then cut off, and finally exhaust from each cylinder in succession. A port y in each cylinder Q serves as an auxiliary exhaust port when uncovered by a piston R and pressure fluid is exhausted into the drum 90 and passes to atmosphere through the ports z in the gear case F . By admitting the supply of motive fluid through the port q instead of through the port p , the direction of rotation of the drum will be reversed. The distributing valve j is in this instance 95 formed with fourteen of the ports r and s seven in each series, and each piston makes seven complete strokes for each revolution of the drum. It is to be understood, however, that the number and position of the ports may be changed, if desired.

In order to control the admission of motive fluid to the motor and the direction of rotation of the drum L , a suitable throttle valve 2 is slidable in the valve chest D' and is in this instance formed with a hollow bore 3 through which motive fluid is adapted to pass to the motor. The valve 2 is provided with heads 4 at the opposite ends thereof 105 controlling the passages 15 and 16 in the head block, which lead to the ports p and q respectively in the distributing valve j of the motor, and in this instance, the heads are formed with serrations 5 to permit gradual control of the pressure fluid. A rack 6 on the valve engages a toothed sector 7 provided with a valve lever 8 by means of which the valve is manipulated. Springs 9 and 10 110 between the ends of the valve 2 and plugs 11 and 12 respectively oppose the movement of the valve in either direction. Motive fluid may be supplied through either plug from the pipe 13, and the opposite plug closed by a suitable cap 14.

In the position of the valve shown in Figure 3, motive fluid passes to the motor through the passage 15, and pressure fluid is exhausted from the motor through the passage 16 and thence to atmosphere through 130

the valve chamber 34. By actuating the handle 8 in the opposite direction, as shown in Figure 4 the direction of rotation of the drum L will be reversed and motive fluid 5 passes through the hollow bore 3 of the throttle valve 2 to the motor through the passage 16; and pressure fluid is exhausted from the motor through the passage 15 and thence to atmosphere through the chamber 10 34.

In order to supply lubricant to the rotating parts of the hoist, a suitable reservoir 17 is formed in the head block D; and is provided with a plurality of filling openings 18, 15 closed by the plugs 19, so that lubricant may be conveniently supplied to the reservoir irrespective of the position of the hoist. A passage 20 is formed in the stationary shaft H and communicates with a spiral groove 21 20 on the outer surface of the shaft, so that the bearing surface of the drum may receive adequate lubrication. Lubricant will also be thrown or carried to the anti-friction thrust bearing 22 on the shaft H and to the 25 cylinders Q through the ports 23. Some lubricant will be blown upon the gears and ring gear, due to the action of the pressure fluid within the drum.

Any suitable brake may be provided for 30 the drum L, and in this instance, a brake lining 24, preferably riveted to a metal band 25, surrounds the drum flange rim P' and one end of the brake band is secured to a shoe 26, on which is pivoted a turnbuckle 27. 35 The opposite end of the brake band is secured to a shoe 28, on which is pivoted a brake lever or handle 29, which carries a screw 30, which is threaded into the turnbuckle 27. A suitable stop is provided for 40 the brake band, and in this instance a shoe 31 is secured to the brake band and is formed with a lug 32, which enters a recess 33 in the base plate A. Pressure exerted upon the lever 29 tightens the brake on the drum L, 45 and controls the rotation of the drum. By adjusting the screw 30 in the turnbuckle 27, the brake may be tightened to compensate for wear.

I am not to be understood as limiting the 50 invention to the particular device and construction shown in the drawings, and described in the specification, since those skilled in the art may devise equivalent constructions within the spirit of the invention, 55 as defined in the appended claims.

I claim:

1. In a fluid actuated rotary cylinder motor hoist, the combination of a support, a rotary winding drum on said support, a 50 rotary cylinder motor within the drum having the longitudinal axes of the cylinders parallel to the longitudinal axis of the drum, a gear outside the drum and pinions bodily rotating with the drum and meshing with 55 said gear and connected to be driven by the

motor whereby the drum is driven by the motor.

2. In a fluid actuated rotary cylinder motor hoist, the combination of a support, a rotary winding drum on said support, a 70 rotary cylinder motor within the drum having longitudinally arranged cylinders formed in the drum, a valve for distributing motive fluid to said cylinders, a stationary gear carried by said support and pinions 75 bodily rotating with the drum and meshing with said gear and connected to be driven by the motor whereby the drum is driven by the motor.

3. In a fluid actuated rotary cylinder 80 motor hoist, the combination of a rotary winding drum, a rotary cylinder motor within the drum having the longitudinal axes of the cylinders parallel to the longitudinal axis of the drum, a valve for distributing 85 motive fluid to said cylinders, pistons adapted to reciprocate in said cylinders, a stationary ring gear outside the drum, pinions bodily rotating with the drum and meshing with said gear and connected to be 90 driven by said motor whereby the drum is driven by the motor, and a throttle valve for controlling the admission of motive fluid to the motor and the direction of rotation of the drum. 95

4. In a fluid actuated rotary cylinder motor hoist, the combination of a support, a rotary winding drum on said support, a rotary cylinder motor within the drum having longitudinally arranged cylinders 100 formed in the drum, a stationary valve for distributing motive fluid to said cylinders, pistons adapted to reciprocate in said cylinders, a stationary ring gear carried by said support outside the drum, pinions bodily 105 rotating with the drum and meshing with said gear and connected to be driven by the motor whereby the drum is driven by the motor and a manually operable throttle valve for controlling the admission of motive fluid to said motor and the direction 110 of rotation of the drum.

5. In a fluid actuated rotary cylinder motor hoist, the combination of a support, a 115 rotary winding drum on said support, a rotary cylinder motor comprising cylinders having their longitudinal axes parallel to the longitudinal axis of the drum, pistons adapted to reciprocate in said cylinders, a bearing plate carried by said drum, crank shafts having bearings on said bearing plate, cranks on said crank shafts, connecting rods connecting said pistons and cranks, pinions carried by said crank shafts, a valve 120 for distributing motive fluid to said cylinders, a ring gear outside said drum with which said pinions mesh and a throttle valve for controlling the admission of motive fluid to said cylinders and the direction 125 of rotation of the drum. 130

6. In a fluid actuated rotary cylinder motor hoist, the combination of a base plate, a support on one end of said base plate, a head block on said support, a gear case on the opposite end of said base plate, a shaft supported at its ends in said head block and gear case, a rotary winding drum on said shaft, a cable on said winding drum, a rotary cylinder motor within the drum having the longitudinal axes of the cylinders parallel to the longitudinal axis of the drum, a gear carried by said gear case outside the drum and pinions bodily rotating with the drum and meshing with said gear and connected to be driven by the motor whereby the drum is driven by the motor.
7. In a fluid actuated rotary cylinder motor hoist, the combination of a base plate, a support on one end of said plate, a gear case on the opposite end of said base plate having a hollow inwardly extending boss, a head block on said support, a shaft supported at its ends in said head block and boss, a rotary winding drum on said shaft,
- a cable on said winding drum, a rotary cylinder motor within the drum having the longitudinal axes of the cylinders parallel to the longitudinal axis of the drum, pistons in said cylinders, a bearing plate carried by said drum, crank shafts supported on said bearing plate, cranks on said crank shafts, connecting rods for connecting said pistons and cranks, pinions carried by said crank shafts, a stationary ring gear carried by said gear case with which said pinions mesh, a stationary distributing valve for distributing motive fluid to said cylinders, a manually operable throttle valve in said head block for controlling the admission of motive fluid to said cylinders and the direction of rotation of said drum, a lubricant reservoir in said head block for distributing lubricant to the operative parts of the hoist and a manually operable brake for said drum.
- In testimony whereof I have signed this specification.

FRED M. SLATER.
